ABSTRACT OF THE DISCLOSURE

An arrangement for the regulation of individual X-ray tubes which are fed from a single high-voltage source and which X-ray tubes have their anodes connected to ground potential. A setting member is connected with each of the X-ray tube circuits and responsive to the X-ray tube current to control a filament transformer also associated with each X-ray tube. A transducer is connected in series with the cathode of each of the X-ray tubes for sensing the current flow through the X-ray tube. Connected to each of the transducers is a regulating device which, in turn, is connected to the setting member for controlling the current flow through the X-ray tube in response to a value selected by the setting member.

A certain measured value has been necessary for an automatic regulation of the X-ray tube current, and dependent on the tube current, for an X-ray apparatus known in the past. The actual value of the regulating magnitude is tapped from a resistor situated on the ground side of the high-voltage circuit. This relatively simple method for obtaining the actual value of the regulating magnitude on the ground side of the high-voltage circuit is possible only in the operation of one X-ray tube. Since in general the X-ray tubes in question operate with grounded anodes and the anodes are cooled with water, a shunt circuit is provided for the cooling in parallel operation of several tubes, making it impossible to exactly obtain the tube current of the individual tube on the grounded anode side.

There is a possibility of circumventing this difficulty by arranging an equal number of secondary windings in the high-voltage generator for several X-ray tubes. The winding end not connected to high-voltage potential can then be connected to ground via a resistor. The resistor can serve as a measuring resistor for a current proportional voltage value. This solution requires, as already mentioned, a separate secondary winding on the high-voltage transformer for each of the tubes to be operated.

In order to avoid this expenditure and not have the main part of the regulating device for the tube currents connected to high-voltage potential, a system for the separate regulation of the tube currents of several X-ray tubes fed from a high-voltage generator is constructed according to the invention in such a way that only one well insulated part of the measuring sensors and of the setting members of the regulating devices for the tube currents are placed on high-voltage potential, and all the other members of the regulating devices are placed at ground potential.

By means of the system according to the invention, the shunt circuits existing through the water cooling of the grounded anodes become inconsequential for the measuring of the individual tube currents, because the actual value of the regulating magnitude is taken on the high-voltage side which is connected to the cathodes of the

2

X-ray tubes. Nevertheless, insulation difficulties are avoided, because a separation is made between high-voltage potential and ground potential in the measuring sensor, so that the greater portion of the regulating circuit is connected to ground potential.

A heating transformer can be used for heating the cathode of the X-ray tube, as a setting member for the regulating device. The primary voltage is delivered from the regulating device. The cathode heating is operated with the voltage from the secondary winding. In the case of X-ray tubes with a Wehnelt cylinder or a control grid, these electrodes can serve as setting members for regulation of the tube current.

In general, it is expedient to arrange grounded potential screens between the high-voltage conducting and the ground side parts of the regulating magnitude.

In different examples of operation of the invention, various measuring sensors are used. Thus, a transducer whose direct current winding is in the high-voltage circuit of the individual X-ray tube can serve as a measuring sensor. The direct current winding is highly insulated with respect to the core of the transducer which is connected to ground potential.

In another example of the operation of the invention, a magnetic field dependent resistor which is arranged in the air gap of a magnet yoke whose field winding lies in the X-ray tube circuit can serve as a measuring sensor. The field windings are highly insulated with respect to the magnet yoke, which is connected to ground potential.

In another example of the operation of the invention, a high-voltage divider is arranged on the high-voltage side. One member of this divider is formed by a resistor controlled by the X-ray tube current. It is possible to tap a control voltage for the regulation of the X-ray tube cathode heating on the low-voltage side of the divider. The resistor in the high-voltage divider circuit can be a high vacuum diode heated by the X-ray tube current and controlled by the tube current. Another solution is to provide a grid-controlled high vacuum tube whose cathode-anode interval serves as a controlled resistor. One control grid of this tube is connected to a measuring resistor in the X-ray tube circuit. A transistor can be used in place of the grid-controlled tube. The emitter collector interval serves as a resistor dependent on the X-ray tube current.

The invention is explained in detail with the aid of five figures which represent examples of the operation. In the figures, like structural parts are provided with the same reference characters.

FIGURE 1 is a schematic wiring diagram of an X-ray circuit according to the present invention;

FIGURE 2 is a schematic wiring diagram showing an alternate form of the X-ray circuit of FIGURE 1;

FIGURE 3 is a schematic wiring diagram showing an alternate form of the X-ray circuit of FIGURE 1;

FIGURE 4 is a schematic wiring diagram showing still another alternate form of the X-ray circuit of FIGURE 1; and

FIGURE 5 is a schematic wiring diagram showing yet another form of the X-ray circuit of FIGURE 1.

In FIG. 1, a high-voltage transformer is designated with T which is connected to a rectifier bridge G1. A capacitor C is provided as a filter. The plus pole of the high voltage bridge is grounded. The minus pole of the bridge is connected via windings W₁, W₂ and W₃ of transducers TK₁ to TK₃ with the cathodes of three X-ray tubes X₁ to X₃. The anodes of the X-ray tubes are connected to ground potential. Control windings of the transducers TK₁ to TK₃ are connected to regulators R₁ to R₃. The outputs of regulators R₁ to R₃, via setting members ST₁ to ST₃, regulate the primary current in the primary windings of heating transformers HT₁ to HT₃ for the heating

of the cathodes of the X-ray tubes. The number of X-ray tubes to be operated in parallel in this manner is dependent only on the power of the high-voltage generator.

In FIG. 2, magnet yokes M_1 and M_2 , whose exciter winding or field winding is traversed by X-ray tube current on the high-voltage side, take the place of the transducers. The iron of the yoke, as well as the core of the transducers, is grounded in the operation according to FIG. 1. Field dependent resistors FW_1 and FW_2 , which are components of a bridge circuit B_1 or B_2 , respectively, are arranged in the air gap of the magnet yokes. The output voltages of the bridges control via setting members ST_1 and ST_2 (again in accordance with the operation as shown in FIG. 1) the primary current of heating transformers HT_1 and HT_2 which supply the heating power for the cathode heating of the X-ray tubes. The secondary windings of the heating transformers are connected to high-voltage potential and are highly insulated against the cores of the heating transformers connected to ground potential.

In the examples of the operation according to FIG. 3, the input voltage for the regulators R_1 and R_2 is tapped at resistors P_1 and P_2 , respectively. These resistors are a component of a high voltage divider circuit, having vacuum diodes D_1 and D_2 connected to high voltage. The cathodes of the vacuum diodes D_1 and D_2 are heated by the X-ray tube currents. The internal resistance of the diodes is thus dependent upon the X-ray tube current. Therefore, the input voltage for the regulator, which is tapped at the resistors P_1 and P_2 , becomes dependent upon the X-ray tube current.

In a further example of the operation according to FIG. 4, the vacuum diodes are replaced by grid-controlled vacuum tubes $Rö_1$ and $Rö_2$. The control voltage of these tubes is tapped at resistors Q_1 and Q_2 , respectively, which carry the X-ray tube currents. A special heating transformer HT_4 provides the heating power for the tubes $Rö_1$ and $Rö_2$.

In an example of the operation execution according to FIG. 5 the grid-controlled high vacuum tubes are replaced by transistors Tr_1 and Tr_2 as components of high voltage divider circuits. The emitter-collector regions of the transistors serve as resistors dependent on X-ray tube current in the voltage dividers. The control voltage for the transistors is regulated by means of resistors Q_3 and Q_4 connected in the X-ray tube current circuit. In the examples of the operation according to FIGS. 2 to 5, more than two X-ray tubes can be operated in parallel on a high-voltage generator.

The regulators R_1 , R_2 and R_3 may be of any suitable design to produce a control voltage which is maintained in accordance with the setting members ST_1 , ST_2 and ST_3 respectively. One such regulating device is shown in the patent to W. E. Splain 3,325,645 and is designated MA stabilizer. Additionally, the setting members ST_1 , ST_2 and ST_3 are used to select the desired amount of current flow through each of the associated X-ray tubes X_1 , X_2 and X_3 respectively. One such setting member which can be used in accordance with the principles of this invention is shown in the patent to C. W. Clapp et al. 2,810,838. Accordingly, neither the regulating members R_1 , R_2 and R_3 nor the setting devices ST_1 , ST_2 and ST_3 in themselves form a part of this invention.

Changes may be made within the scope and spirit of the appended claims which define what is believed to be new and desire to have protected by Letters Patent.

I claim:

1. An arrangement for the separate regulation of a plurality of X-ray tubes which are operated from a single high-voltage source, comprising: a high-voltage source; a plurality of X-ray tubes each having their anode connected to ground potential and their cathode connected to said high-voltage source, each of said X-ray tubes having a heater filament; a plurality of filament transformers, each filament transformer having its secondary winding

connected to the heater filament of its associated X-ray tube, and further having a primary winding; a control circuit connected to each of said X-ray tubes to control the amount of heating current applied to the associated heating filament, each of said control circuits including, 5 electromagnetic sensing means including an electromagnetic transducer having a winding which is insulated from ground potential and connected in series with the cathode circuit of the associated X-ray tube operative to sense the actual amount of direct current passing through said winding and thus through the X-ray tube, a setting member for selecting a desired amount of current to pass through the associated X-ray tube, regulator means connected between said sensing means and said setting member to compare the actual amount of current passing through the associated X-ray tube with that of the desired amount of current thereby producing a control voltage, and circuit means connecting the primary winding of said filament transformer with said regulator means, whereby, 15 said control voltage will control the amount of heating current applied to the heater filament of the associated X-ray tube.

2. An arrangement for the separate regulation of a plurality of X-ray tubes which are operated from a single high-voltage source, comprising: a high-voltage source; a plurality of X-ray tubes each having their anode connected to ground potential and their cathode connected to said high-voltage source, each of said X-ray tubes having a heater filament; a plurality of filament transformers, 25 each filament transformer having its secondary winding connected to the heater filament of its associated X-ray tube, and further having a primary winding; a control circuit connected to each of said X-ray tubes to control the amount of heating current applied to the associated heating filament, each of said control circuits including, 30 electromagnetic sensing means connected in series with the associated X-ray tube for sensing the actual amount of direct current passing through the X-ray tube, a setting member for selecting a desired amount of current to pass through the associated X-ray tube, regulator means connected between said sensing means and said setting member to compare the actual amount of current passing through the associated X-ray tube with that of the desired amount of current thereby producing a control voltage, circuit means connecting the primary winding of said filament transformer with said regular means, whereby, 35 said control voltage will control the amount of heating current applied to the heater filament of the associated X-ray tube, said sensing means being formed by a field winding of a magnetic yoke and further including a magnetic field dependent resistor responsive to the magnetic field produced by said magnetic yoke, said magnetic field dependent resistor being connected to said regulator means.

3. An arrangement for the separate regulation of a plurality of X-ray tubes according to claim 2 wherein said magnetic yoke is connected to ground potential.

4. An arrangement for the separate regulation of a plurality of X-ray tubes which are operated from a single high-voltage source, comprising: a high-voltage source; 60 a plurality of X-ray tubes each having their anode connected to ground potential and their cathode connected to said high-voltage source, each of said X-ray tubes having a heater filament; a plurality of filament transformers, each filament transformer having its secondary winding connected to the heater filament of its associated X-ray tube, and further having a primary winding; a control circuit connected to each of said X-ray tubes to control the amount of heating current applied to the associated heating filament, each of said control circuits including, 65 sensing means connected in series with the associated X-ray tube for sensing the actual amount of direct current passing through the X-ray tube, a setting member for selecting a desired amount of current to pass through the associated X-ray tube, regulator means connected between said sensing means and said setting member to compare

the actual amount of current passing through the associated X-ray tube with that of the desired amount of current thereby producing a control voltage, circuit means connecting the primary winding of said filament transformer with said regulator means, whereby, said control voltage will control the amount of heating current applied to the heater filament of the associated X-ray tube, said sensing means including the filament of an electron tube connected in series with the direct current of the associated X-ray tube, the conduction of said electron tube being proportional to the current passing through said X-ray tube, and a voltage divider connected in series with said electron tube, the output of said voltage divider being connected to said regulator means.

5. An arrangement for controlling the separate regulation of a plurality of X-ray tubes according to claim 4 wherein said electron tube is a diode.

6. An arrangement for the separate regulation of a plurality of X-ray tubes which are operated from a single high-voltage source, comprising: a high-voltage source; a plurality of X-ray tubes each having their anode connected to ground potential and their cathode connected to said high-voltage source, each of said X-ray tubes having a heater filament; a plurality of filament transformers, each filament transformer having its secondary winding connected to the heater filament of its associated X-ray tube, and further having a primary winding; a control circuit connected to each of said X-ray tubes to control the amount of heating current applied to the associated heating filament, each of said control circuits including, sensing means connected in series with the associated X-ray tube for sensing the actual amount of direct current passing through the X-ray tube, a setting member for selecting a desired amount of current to pass through the associated X-ray tube, regulator means connected between said sensing means and said setting member to com-

pare the actual amount of current passing through the associated X-ray tube with that of the desired amount of current thereby producing a control voltage, circuit means connecting the primary winding of said filament transformer with said regulator means, whereby, said control voltage will control the amount of heating current applied to the heater filament of the associated X-ray tube, said sensing means including a resistor connected in series with the current passing through the associated X-ray tube, and a variable conduction device connected to said resistor, and a voltage divider network connected to said variable conduction device, said voltage divider network having the output thereof connected to said regulator means.

15 7. An arrangement for the separate regulation of a plurality of X-ray tubes according to claim 6 wherein said variable conduction device is an electron tube.

8. An arrangement for the separate regulation of a plurality of X-ray tubes according to claim 6 wherein said 20 variable conduction device is a transistor.
